LATCH BAR HAMMER FOR DIPPER BUCKETS

Lewis E. Younie, Portland, Oreg., assignor to
Electric Steel Foundry Company, Portland,
Oreg.

Application April 13, 1935, Serial No. 16,229

4 Claims. (Cl. 292—186)

This invention relates generally to excavating machinery and particularly to a latch bar hammer for dipper buckets.

The main object of this invention is the provision of an improved form of latching mechanism for dipper buckets whereby the latch will function properly at all times, even when handling heavy sticky materials.

A secondary object is to cause the latch to be driven forcibly by an impact both in latching and unlatching directions.

These, and other objects, will become more apparent from the specification following as illustrated in the accompanying drawing, in which:

Fig. 1 is a perspective view of the gate end of a dipper bucket showing the device in a latched position.

Fig. 2 is a fragmentary section taken along the line 2—2 in Fig. 1.

Fig. 3 is a fragmentary section taken along the line 3—3 in Fig. 1.

Fig. 4 is a fragmentary section taken along the line 4—4 in Fig. 1 showing the gate about to close.

Fig. 5 is a view similar to Fig. 4, but showing the gate closed and the plug being forcibly ejected by the latch.

Fig. 6 is a section through a modified form of the latching mechanism.

Similar numbers of reference refer to similar parts throughout the several views.

Referring in detail to the drawing, there is shown a common form of dipper bucket whose front 10 is attached to the sides 11 and whose door or bottom 12 is hinged to the rear side of the bucket by means of the arms 13 and pins 14.

The front 10 is provided with a latch plate 15 having an opening 16 which receives the latch bar 17, which is slidably mounted in the latch bar housing 18. The housing 18 is secured to the door 12 by means of the cross braces 19. The foremost end 20 of the latch bar 17 is beveled to facilitate the latching operation.

To the rearmost end of the latch bar 17 is attached a lever 21 by means of a pin 22. The lever 21 is fulcrumed on the pin 23 which is adjustably supported by means of the eye bolt 24 and nut 25 which latter rests upon the rearmost brace member 19.

Secured to the door 12 is a guide 26 in which is slidably mounted a hammer 27 to one end of which is secured an operating chain 28. The chain 28 may be secured to a lug 29 on the forward end of the hammer 27 if the construction of the bucket renders this desirable.

Extending through the hammer 27 is a longi-

tudinal slot 30 through which is slidably passed the lever 21. It is desirable to provide guides 31 on the door 12 for the lever 21.

The operation of this form of the device is as follows:

The hammer 27 is normally in the position shown in Fig. 1, that is, resting upon the lever 21. If it is desired to unlatch the bucket, the operator merely exerts a pull on the chain 28, causing the hammer 27 to move. The first position of its movement, however, does not affect the lever 21 until the end of the slot 30 is reached, which causes a sharp blow to be struck against the forward side of the lever 21, and withdrawing the latch bar 17 from the opening 16.

The same is true of the closing operation as shown in Fig. 5 in which a return movement of the hammer 27 will cause a sharp blow to be struck against the latch bar 17 and forcibly eject the plug 32 from the opening 16.

In the form of the device shown in Fig. 6, the lever 21 extends through the slot 33 of a tubular guide 34 within which is disposed a hammer 35, which is preferably cushioned against a spring 36. The guide 34 is secured on the door 12 and corresponds with the guide 26. Also fastened on the door 12 is a tubular guide 37, through which passes an operating chain 38, which is secured to the lever 21.

The operation of this form of the device is similar to that shown in Figs. 1 to 4 inclusive, except that the blow is struck only on the latching movement of the lever 21 instead of in both directions as in the first described form of the device.

Obviously, this may be accomplished in many different ways without departing from the spirit of this invention. I therefore do not intend to be bound by the particular form shown in the drawing or described in the specification, but intend to cover all such forms of the device as fall fairly within the appended claims.

In the modification shown in Fig. 6 the operating chain 38 is attached directly to the lever 21 while the weight 35 is raised by the lever 21; that is to say, it can strike a blow only for the purpose of driving out the plug 32, whereas in the preferred form of the device shown in Fig. 1, the chain 28 is attached to the hammer 27 which is capable of driving the lever 21 in either direction.

I claim:

1. In a dipper bucket having a hinged door at its rearmost end, a latch at the swinging end of said door, said latch engaging an opening at the bucket front, means for manually withdrawing

said latch from said opening and a hammer for forcing said latch into said opening when brought into register therewith.

2. In a dipper bucket having a door at the outlet thereof and hinged to the rear side of the bucket and latched to the front side thereof, a latching mechanism consisting of a latch and keeper for holding said door in a closed position, a lever for actuating said latch, a movable weight 10 associated with said lever and adapted to impart a striking blow thereto in a manner to force said latch into said keeper when said door is in a closed position.
3. In a dipper bucket having the bottom there-
15 of in the form of a door hinged at its rearward side to said bucket and having a latch bar mount-

ed on said door adapted to engage a keeper in said bucket, a mechanism for operating said latch bar consisting of a chain for operating said bar in one direction and a weight actuated by said bar for driving the same by impact in an opposite direction. 5

4. A latching mechanism for dipper buckets consisting of a latch bar and keeper, a lever for actuating said latch bar, a slotted hammer through which said lever extends and means for 10 raising said hammer in a manner to strike a blow against said lever and permitting said hammer to strike a blow on said lever in an opposite direction under the action of gravity.
